WELL BORING APPARATUS

Archer W. Kammerer, Fullerton, Calif.

Application October 13, 1947, Serial No. 779,591

10 Claims. (Cl. 255—76)

1

This invention relates to well boring apparatus, and more particularly to rotary drill bits of the expandable type for drilling or reaming holes below well casings greater in diameter than the inside diameter of casing through which the bits are capable of passing.

This invention is a continuation-in-part of my applications for "Rotary Drill Bits," Serial No. 597,744, filed June 6, 1945, now Patent No. 2,466,991, and "Expandible Rotary Drill Bits," Serial No. 686,806, filed July 29, 1946.

In the devices disclosed in the aforementioned applications, cutter means are expanded outwardly and are held outwardly by a suitable lock device, which prevents their inadvertent retraction and forestalls the drilling of an undersized hole. An object of the present invention is to provide for improved cooperation between the cutter means of an expandible drill bit and the main bit body, the cutter means being guided in better fashion in its lateral movement between retracted and expanded positions.

A further object of the invention is to provide an expandible rotary drilling bit whose cutters are held in their expanded position by a device capable of automatically aligning itself with respect to the cutters, but whose relative rotary movement with respect to the cutters is limited by guiding means provided on the main body of the tool itself. More specifically, the locking device is capable of holding the cutter means in their outward expanded position without transmitting drilling torque thereto.

Another object of the invention resides in the provision of an expandible rotary drill bit, in which alignment and registry of the relatively movable parts is assured, to obtain better operation of the bit and enhancement of its useful life.

The invention has other objects which will become apparent from a consideration of the embodiment shown in the drawings accompanying and constituting part of the present specification. This form will now be described in detail to illustrate the general principles of the invention, but it is to be understood that such detailed description is not to be taken in a limited sense, since the scope of the invention is best defined by the appended claims.

Referring to the drawings:

Fig. 1 is a side elevation of one form of expandible drill bit embodying the invention.

Fig. 2 is a longitudinal section through the drill bit on an enlarged scale, with the parts shown in retracted position for enabling the bit to be lowered through the well bore.

Fig. 3 is a view similar to Fig. 2, with the parts disclosed in expanded position.

Fig. 4 is a cross-section taken along the line 4—4 on Fig. 2.

2

Fig. 5 is a cross-section taken along the line 5—5 on Fig. 3.

Fig. 6 is a partial longitudinal section taken along the line 6—6 on Fig. 3.

Fig. 7 is a partial side elevation of the bit illustrated in Fig. 1, but presented on an enlarged scale for purposes of clarity.

Fig. 8 is a cross-section taken along the line 8—8 on Fig. 2.

10 As shown in the drawings, the expandible rotary drill bit A is attached to a string of drill pipe B by means of which it is lowered through a well casing C in the well bore to a point below the casing shoe D at which enlargement of the bore 15 hole is to commence. The drill bit preferably has a pilot bit 10 at its lower end for centering the tool in a hole that may have already been drilled, or for drilling the central portion of new hole in the absence of a pre-existing hole. The 20 main portion of the bit is capable of enlarging the bore hole by producing and operating upon a formation shoulder E, as hereinafter described.

The upper end of the bit consists of a driving mandrel 11 whose upper pin 12 is threadedly 25 connected to a sub 13, forming the lower end of the drill pipe string B. This mandrel includes an upper kelly or drill stem member 14 slidably splined to the main body 15 of the bit. As disclosed in the drawings (see Fig. 4), the exterior 30 14a of the kelly is hexagonal in shape, and is telescopically received in a companion hexagonal socket 15a within the body. The mandrel 14 has a limited range of longitudinal movement within the body, its upward movement being determined 35 by engagement of an external shoulder 16 on the kelly with a retainer ring 17 suitably secured to the upper end of the body 15, as by the use of welding material 18.

The body 15 has a plurality of expandible parts 40 mounted on it, comprising opposed cutter supporting members 19, 19 pivotally carried between bifurcated body arms 20, 20 on pivot or hinge pins 21, 21 suitably secured to the arms, as by welding material 22. The arms define the sides of a 45 transverse slot 60 extending through the body, in which the supporting members 19 are mounted. Each cutter supporting member consists of a depending leg 23 having a bearing supporting pin 24 inclined inwardly and downwardly and on 50 which is rotatably mounted a roller side cutter 25. Anti-friction roller and ball-bearing elements 26, 27 are preferably placed between each cutter 25 and bearing pin 24, the roller bearings 26 transmitting radial thrusts, and the ball bearings 27 both radial and axial thrusts.

Each cutter supporting member 19 also includes an upwardly extending arm 30 against which an elastic expander 31 bears. This expander is in the form of a compressed coil spring 55 received within a retainer pocket 32 in the body

15. exerting its force against the arm 30 and tending to swing it inwardly and thus urge the cutter 25 on the other side of the fulcrum pin 21 in an outward direction. The extent of this outward movement is limited by engagement of stop shoulders 33, 33 on opposite sides of the cutter supporting member 19 with cooperable body stop shoulders 34, 34.

After each cutter 25 has been expanded outwardly by its cooperable expander spring 31 to the maximum extent, it can be locked in this position by a tubular member 35 of the mandrel 11, which is piloted in the kelly 14 and is provided with a lock portion 47. The latter is movable from an upper position in transverse alignment with inner supporting member recesses 36, permitting retraction of the cutters, to a lower position opposite lugs 37 formed on and projecting inwardly from the supporting member legs 23, preventing retraction of the cutters 25.

The tubular member 35 is connected in swivel fashion to the kelly 14 to permit relative arcuate or rotary movement therebetween. However, the kelly and tubular member are movable together for longitudinal movement in both directions. This is accomplished by providing a stop shoulder 39 on the tubular member, received within a lower socket 14b in the kelly and abutting a companion shoulder 14c in the kelly at the upper end of the socket. The tubular member 35 has an upper portion 35a extending from the shoulder 39 freely through the central bore 14d of the kelly, with the upper terminus of the upper member 35a received within an enlarged recess 14e in the kelly or mandrel pin 12 where a nut 35b is threaded on the terminal portion, bearing against the base 14f of the upper pin recess 14e.

The arrangement between the tubular member 35 and kelly 14 is such that downward movement is transmitted from the kelly to the tubular member through the abutting shoulders 14c, 39, while upward movement is transmitted to the tubular member through engagement of the recess shoulder 14f with the nut 35b. However, the nut 35b does not serve to clamp the tubular member 35 to the kelly 14, but allows relative rotary movement therebetween.

The mandrel 11 is normally held in its upper position with respect to the main body 15 of the bit and the supporting members 19 by a helical retractor spring 38 encircling the tubular member 35, with its upper end engaging the mandrel shoulder 39 and its lower end engaging a spring seat 40 at the lower end of the hexagonal body socket 15a, the spring seat serving as an upper bearing guide for the tubular mandrel member 35. As described below, the tubular mandrel member 35 is movable downwardly to engage the cutter legs 23 and resist their inward movement to retracted position during the reaming or cutting operation.

Circulating fluid can pass downwardly through the string of drill pipe D and through the tubular mandrel 11 for ejection from its lower discharge nozzle 35c and onto the cutters 25, to cleanse them of cuttings and flush the latter from the drilling area to the top of the well bore. This circulating fluid is also available to unlock the cutter supporting members 19, in the event they are first held positively in retracted positions by a locking device, described below.

A positive lock may be provided by securing a hook 42 to the inner portion of each cutter supporting member and inserting the ends 43 of these hooks in holes 44 in a strip 45 extending across

the outlet 35c of the mandrel. The cutting tool A, after being lowered in retracted position to the point at which the reaming operation is to begin, may be released for operation by starting the pumps at the surface of the well bore, which will force fluid down through the drill string D and mandrel 11 for impinging upon the latch strip 45, blowing or forcing it off the hook ends 43, and permitting the spring expanders 31 to shift the supporting arms 30 inwardly and the cutters 25 outwardly against the formation.

In the operation of the device, the tool A is mounted on the lower end of the drill string B, with its parts held in retracted position by the latch strip 45, as shown in Fig. 2. In this position of operation, the compressed retractor spring 38 holds the mandrel 11 and kelly 14 in an upward position with respect to the body 15, as determined by engagement of the kelly shoulder 16 with the body retainer ring 17. With the mandrel in this position, the lock portion 47 is elevated above the lugs 37 on the cutter supporting members 19, being received within the inner recesses 36 in the supporting members, which permits the latter to be held inwardly against the action of the expander springs 31. The tool is lowered through the well casing C, and upon reaching the position in the well bore below the casing shoe D at which the drilling operation is to begin, the pumps are started at the surface of the well bore, and fluid impinged on the latch strip 45, forcing it hydraulically off the ends 43 of the hooks 42 and releasing the cutter supporting members 19 for outward expansion under the influence of the springs 31.

The drill string B is then rotated to rotate the main bit body 14 through the splined kelly and body connection 14a, 15a, the expander springs 31 forcing the arms 30 inwardly and the cutters 25 outwardly against the formation. Rotation is continued without moving the drill string B longitudinally until the side cutters 25 enlarge the diameter of the hole to the maximum extent as determined by the eventual abutting of the supporting member stop shoulders 33 with the companion body stop shoulders 34. Thereafter, the drill string is lowered to cause the formation shoulder E, produced in the well bore by the cutters 25 under the action of the expander springs 31 and rotation of the tool, to support the cutter members 25, 19 and body 15 and prevent their downward movement.

Since the body 15 cannot move downwardly, drilling weight imposed on the drilling string 55 B shifts its connected mandrel 11 downwardly within the body 15 against the action of the retractor spring 38 until the lower end 48 of the kelly 14 engages the upper spring seat and guide 40 (see Fig. 3). This downward movement also shifts the tubular member 35 downwardly because of the abutting between the kelly and tubular member shoulders, 14c, 39, to position the mandrel or tubular member lock portion 47 opposite and in alignment with the lugs 37 on 60 the inner portions of the cutter supporting members 19, providing a positive lock by preventing inward movement of the cutters. So long as down weight is imposed on the drill string B, and the cutters 25 rest on the formation shoulder 65 E, the cutters are prevented from moving inwardly by engagement of their lugs 37 with the mandrel lock portion 47. It is also to be noted that further outward movement of the cutters beyond the predetermined maximum diameter 70 75 is prevented by contact between the supporting

member shoulders 33 and the body shoulders 34, through which the drilling weight is transmitted to the roller cutters 25, thus relieving the hinge pins 21 of this load.

Drilling is continued by rotating the drill bit and imposing the proper drilling weight on the cutters, to cause their removal of the formation material and reaming of the hole in a downward direction for the desired extent or length. When the drill bit is to be retracted and removed to the top of the well bore, all that need be done is elevate the drill string B, which moves the side cutters 25 above the formation shoulder E and permits the retractor spring 38 to press downwardly on the body 15 and move it, together with the cutter supporting members 19, downwardly with respect to the mandrel 11. This action repositions the mandrel lock portion 47 opposite the supporting member recesses 36 and above their lugs 37, because of the engagement between the pin recess shoulder 14f and tubular member nut 35b, permitting inward swinging of the cutters 25 and their supporting members 19 when the tool passes back into the casing C upon elevation of the drill string. Cutters 25 and their supporting members 19 will ride the wall of the casing C during elevation of the string until the tool is removed from the top of the well bore.

Pads in the form of longitudinal drag reaming blades 46 can be formed at the lower outer surfaces of the cutter supporting members 19, which will ride the inner wall of the casing and prevent the cutter teeth from hanging up in the casing coupling spaces while the tool is being lowered therein. These pads 46 can be provided in addition to the hooks 42 and latch strip 45, or in place of the latter. When the latching device is used, the tool can be lowered through open hole below the casing shoe D for as far a distance as is desired before the reaming operation commences. If the latch is not provided, downward movement of the drill string B can be stopped when the bit passes out of the shoe D and the drill pipe B and bit A to allow the cutters 25 to produce the formation shoulder E under the influence of the compressed expander springs 31. Drilling in a downward direction can then proceed as aforementioned, with the drill string B and mandrel 11 lowered against the action of the retractor spring 38 to position the lock portion 47 opposite the lugs 37 and prevent inward movement of the cutters until the drilling weight is removed from the drilling tool.

The lock portion 47 of the tubular member preferably has flat faces 47a engaging corresponding flat faces 37a on the lugs 37 extending inwardly from the cutter supporting members 19. These flat faces are preferred to provide a surface contact between the members and thus increase the load carrying capacity of the lock device, enabling it to resist to a greater extent the reactive force of the formation tending to press the cutters 25 inwardly from their expanded positions. The remaining portions of the tubular member 35, namely, the shoulder 39, the upper section 35a above the shoulder, and the portion which rides in the bearing guide 40, are all circular in cross-section to permit relative rotation, even to a slight extent, between the tubular member 35 and the kelly 14 within which it is received.

It is to be noted that relative rotation, at least to a slight extent, between the tubular member

35 and its locking portion 47 with respect to the driving kelly 14 is permitted, and this relative rotation is important, since it permits the lock portion 47 to adjust itself with respect to the lugs 37 on the cutter supports 19, and thus insure a surface contact therebetween, providing a large load-carrying capacity in the lock portion 47. If the tubular member 35 were incapable of swivelling or moving about the bit axis, line contact might result between the cutter lugs 37 and the lock portion 47 of the tubular member, producing concentrated wear on both of these parts during their resistance to the formation reactive forces, tending to press the cutters 25 inwardly from their retracted positions. Such wear would permit the cutters to shift inwardly and would result in the production of a reamed hole of lesser diameter than that desired.

As is pointed out in my above identified application, Serial No. 686,806, there is still a further advantage to the swivel or relatively oscillatable connection between the tubular lock member 35 and the driving kelly 14. Although the kelly is telescopically splined to the body 15, a slight amount of relative arcuate movement between them can occur because of the working clearances that must be maintained between the hexagonal kelly 14a and hexagonal socket 15a in the body. The rigid attachment of the tubular lock member 35 to the kelly 14 would result in angular movement of the lock portion 47 with respect to the cutter supports 19 during the drilling operation, and would result in line contact between the lock portion 47 and lugs 37, rather than the desirable surface contact. The swivel connection prevents the transmission of such relative angular movement of the kelly 14 with respect to the body 15 through the tubular member 35, since the latter is rotatable in the kelly and is unaffected by the turning movement of the latter. None of the drilling torque transmitted through the driving kelly 14 to the body 15 passes through the tubular member 35 and its locking portion 47 onto the supporting members 19.

To further offer assurance that the locking portion 47 and the lugs 37 will engage one another along a surface contact, the upper portion of the longitudinal groove 60 between the bifurcated arms 20, 20, extending completely transversely through the main body 15 of the tool, has parallel side walls 61 which make a slidable fit with the sides 19a of the cutter supporting members 19. In addition, the lock portion 47 of the mandrel also has its opposed surfaces 47b, at right angles to its lug contacting surfaces 47a, parallel to one another and adapted to have slidable contact with the walls 61 of the transverse slot or groove 60.

The provision of the slidable contact between the walls 61 of the slot and the sides 19a of the cutter supporting member, on the one hand, and with the sides 47b of the lock portion 47 of the mandrel 11, on the other hand, insures the alignment or registry of all the parts with respect to each other, and also insures the surface contact between the lock member 47 and the lugs 37 on the supporting members. The sides 61 of the longitudinal slot 60 can be machined accurately and parallel to one another, which is also true of the sides 19a of each cutter supporting member 19. Moreover, the surface 37a of the lug 37 of each supporting member can be machined at right angles to the side

surfaces 19a of the cutter supporting member, and the side guiding surfaces 47b of the lock portion of the mandrel can be machined perpendicular to its lug engaging surfaces 47a. The distances between the parallel surfaces 19a are made equal to the distance between the parallel surfaces 47b, and this dimension is only slightly less than the distance between the parallel slot walls 61, to allow proper working clearance between the several parts. The walls, however, serve to slidably guide the cutter supporting members 19 and the lock 47 in their respective movements.

It becomes apparent that following assembly of the parts, the side walls 61 of the slot 60 cooperate with the sides 47b of the lock portion to hold their lock surfaces 47a at right angles to the slot walls. Similarly, the sides 61 of the slot cooperate with the companion sides 19a of the cutter supporting members to insure that the lug surfaces 37a will be disposed at right angles to the walls 61 of the slot. This arrangement insures that the lock surfaces 47a of the lock portion of the mandrel will be parallel to the companion surfaces 37a on the lugs 37 when the cutters 25 are in their outwardly expanded position, which provides the desired surface contact therebetween.

It is to be noted that despite the guiding of the lock portion 47 of the mandrel by the walls 61 of the slot during longitudinal movement of the former, and the registering of the lock surfaces 47a by the walls of the slot with the companion surfaces 37a of the cutter supporting member lugs 37, the swivel connection is still provided between the kelly 14 and the tubular mandrel 35. This will prevent the drilling torque from being transmitted through the locking device 47 to the cutter supporting members 19. However, the working clearances that still must be provided between the lock portion 47 of the mandrel 11 and the walls 61 of the slot still permit slight angular movement of the mandrel member 35 with respect to the main body 15 of the bit and insures the adjustability of the locking device 47 with respect to the cutter supporting members 19 and the provision of a surface contact between their coengaging parts.

It is, accordingly, apparent that an expandable rotary drill bit has been provided, in which alignment and registry between the relatively movable parts are obtained, thus giving the entire tool a greater load transmitting capacity, and providing assurance against the reaming or drilling of an undersized well bore. The relationships between the parts is such that their machining to proper dimensions and their appropriate assembly are comparatively simple to perform.

Having thus described my invention, what I claim and desire to secure by Letters Patent is:

1. A rotary well drilling bit: including a body having a transverse slot therein; cutter means mounted on said body within said slot; means for expanding and holding said cutter means laterally outward, said expanding and holding means comprising a first member connectable to a drill string and movable in a longitudinal direction along said body, a second member rotatably connected to said first member for longitudinal movement therewith and engageable with said cutter means for holding said cutter means laterally outward; said cutter means and second member having guiding surfaces in

slidable contacting relation to guiding surfaces provided by the walls of said slot.

2. A rotary well drilling bit: including a body having a transverse slot therein; cutter means mounted on said body within said slot for lateral movement with respect to said body; means for expanding and holding said cutter means laterally outward, said expanding and holding means comprising instrumentalities connectable to a drill string and movable in a longitudinal direction along said body into engagement with said cutter means for holding said cutter means laterally outward; said cutter means and instrumentalities having guiding surfaces in slid- 15 able contacting relation to guiding surfaces provided by the opposed walls of said slot during lateral movement of said cutter means and longitudinal movement of said instrumentalities.

3. A rotary well drilling bit: including a body having opposed walls parallel to each other and defining a transverse slot therebetween; cutter means mounted on said body within said slot for lateral movement with respect to said body; means for expanding and holding said cutter means laterally outward, said expanding and holding means comprising instrumentalities connectable to a drill string and movable in a longitudinal direction along said body into engagement with said cutter means for holding said cutter means laterally outward; said cutter means and instrumentalities each having parallel guiding surfaces in slidable contacting relation to said walls of said body during lateral movement of said cutter means and longitudinal movement of said instrumentalities.

4. A rotary well drilling bit: including a body having opposed walls parallel to each other and defining a transverse slot therebetween; cutter means mounted on said body within said slot; means for expanding and holding said cutter means laterally outward, said expanding and holding means comprising a first member connectable to a drill string and movable in a longitudinal direction along said body, a second member rotatably connected to said first member for longitudinal movement therewith and engageable with said cutter means for holding said cutter means laterally outward; said cutter means and second member each having parallel guiding surfaces in slidable contacting relation to said walls of said body.

5. A rotary well drilling bit: including a body having opposed walls parallel to each other and defining a transverse slot therebetween; cutter means mounted on said body within said slot; means for expanding and holding said cutter means laterally outward, said expanding and holding means comprising a first member slidably splined to said body and movable in a longitudinal direction along said body, a second member swivelly connected to said first member for longitudinal movement therewith and engageable with said cutter means for holding said cutter means laterally outward; said cutter means and second member each having parallel guiding surfaces in slidable contacting relation to said walls of said body.

6. A rotary well drilling bit: including a body having opposed walls parallel to each other and defining a transverse slot therebetween; cutter means mounted on said body within said slot; elastic means engaging said cutter means for expanding said cutter means laterally outward; a lock device movable in one longitudinal direction along said body to a position preventing in-

ward movement of said cutter means from its outwardly expanded position, said lock device comprising a first member splined to said body and a second member rotatable with respect to said first member and engageable with said cutter means, said second member being connected to said first member for longitudinal movement therewith; said cutter means and second member each having parallel guiding surfaces in slidable contacting relation to said walls of said body.

7. A rotary well drilling bit: including a body having opposed walls parallel to each other and defining a transverse slot therebetween; cutter means mounted on said body within said slot for lateral movement with respect to said body; elastic means engaging said cutter means for expanding said cutter means laterally outward; a lock device movable in one longitudinal direction along said body to a position preventing inward movement of said cutter means from its outwardly expanded position, said lock device comprising a first member connectible to a drill string and slidably splined to said body and a second member engageable with said cutter means; swivel means connecting said first and second members together for joint longitudinal movement and for angular movement with respect to each other; said cutter means and second member each having parallel surfaces in slidable contacting relation to said walls of said body during lateral movement of said cutter means and longitudinal movement of said members.

8. A rotary well drilling bit: including a body having opposed walls parallel to each other and defining a transverse slot therebetween; cutter means mounted on said body within said slot for lateral movement with respect to said body; means for expanding and holding said cutter means laterally outward, said expanding and holding means comprising a first member connectible to a drill string and slidably splined to said body, a second member engageable with said cutter means for holding said cutter means laterally outward, swivel means connecting said first and second members together for joint longitudinal movement and for angular movement with respect to each other; said cutter means and second member each having parallel surfaces in slidable contacting relation to said walls of said body during lateral movement of said cutter means and longitudinal movement of said members.

9. A rotary well drilling bit: including a body having a transverse slot therein; cutter means mounted on said body within said slot for lateral

movement with respect to said body; means for expanding and holding said cutter means laterally outward, said expanding and holding means comprising a first member connectible to a drill string and movable along said body, a second member engageable with said cutter means for holding said cutter means laterally outward, swivel means connecting said first and second members together for joint longitudinal movement and for angular movement with respect to each other; said cutter means and second member having non-cylindrical guiding surfaces in slidable contacting relation to guiding surfaces provided by the walls of said slot during lateral movement of said cutter means and longitudinal movement of said members.

10. A rotary well drilling bit: including a body; cutter means mounted on said body for lateral movement with respect to said body; means for expanding and holding said cutter means laterally outward, said expanding and holding means comprising a first member connectable to a drilling string and slidably splined to said body, a second member engageable with said cutter means along a surface of contact substantially normal to the direction of lateral movement of said cutter means relative to said body, means rotatably connecting said second member to said first member; said body and second member having surfaces in engagement with each other substantially parallel to the direction of lateral movement of said cutter means relative to said body to limit the extent of relative rotation between said second member and first member.
